(57) CLAIM

The ornamental design for an exercise strap, as shown and described.

DESCRIPTION

FIG. 1 is a front perspective view of an exercise strap showing my new design;

FIG. 2 is a front elevational view thereof;

FIG. 3 is a rear elevational view thereof; and,

FIG. 4 is a rear perspective view thereof.

The broken lines in the drawings show stitching that form no part of the claimed design.
